J. Henderson & C. K. Watson.

Tailors' Measure.

No. 6807X

Patented Oct. 22. 1831.

James Henderson & Cooper R. Watson, Zanesville
Ohio

Letters Patent.

The Schedule referred to in these Letters Patent and making part of this
Document containing a description in the words of the said James Henderson
and Cooper R. Watson themselves of their improvement in measuring for
and cutting Garments.

To all to whom these presents shall come: We do know that the
James Henderson and Cooper R. Watson of Zanesville in the County
of Muskingum and State of Ohio have invented a new and useful
improvement in the art of measuring for and cutting garments. And
the following is a full and exact description of the construction and op-
eration of said improvement as invented and improved by us.

There is an upright Standard of sufficient length to include the height of
the tallest person, say seven feet. This is divided into inches commen-
cing at the bottom. On this upright are three slides, ²⁶ presented in the
drawing Fig 1. A being the Standard and B.C and D the three slides
which work up and down, and are kept in their place by means of ^{springs} ^{on} ^{the} ^{standard}.
There is a scale (Fig 1.) of not less than thirty six inches in length
which works in a groove in the upright Standard and is made fast by
screws to the top slide B. so that when the slide is moved up or down
on the Standard the scale will move in the groove.

This scale is divided into inches commencing at the top which division of inches is marked on one side or edge of the scale. which is divided
by a perpendicular line running the whole length. the other side or edge
is divided into parts equal to two thirds of an inch commencing at the
top as represented in Fig 1. There are three arms F F E which
run through the slides B.C & D horizontally are movable in the
slides and work at right angles with the Standard. The part
concerned to be measured is to stand upon the small platform E on
which the Standard is placed with his back to the Standard, the

one end of the scale

slide B then is so placed or lifted on the standard that it and F will touch the bottom of the neck or socket bone, the arm of this arm of the slide D is then laid between his legs and moved upright in the circle. By this means the number of inches between B and D are marked on the moving scale at the slide D which number is the exact length of the body in a perpendicular line. The slide C is then moved to that number on the other edge of the moving scale corresponding to the number of inches between B and D. That is to point at exactly two thirds of the distance from B to D. this point may be termed the balancing or permanent point for the waist and may be varied from a fashion strange; by a scale by which the proportion may be made for an individual of any given size.

Before this much of the measure is taken, a leather strap is placed around the breast, close under the arm, on this strap is a small strap passing down the centre of the back and at right angles with the broad strap. The perpendicular strap is drawn to the waist by a strap placed around that part. by this means the centre of the back is sustained when the measure is applied. The broad strap is sustained by small straps which pass over each shoulder and are fastened by buckles or slides a small standard (represented by Fig. 2) of the same height with the one described (with a square at the foot so that it may stand perpendicular, and provided with a slide and arm as the other standard) is then used by applying the arm to the centre of the breast, the centre of the back and under each arm, to ensure that the straps pass around the body in a true horizontal line. Then by the shoulder straps, which must join the broad strap at right angles is sustained the joint of the shoulder. Then from the front (see Fig. 3, where the shoulder and Breast straps join in front of the shoulder the following measures are to be taken which are marked with corresponding numbers on the draft (of Fig. 3. of the drawings) 1st Under the arm to the joint on the broad strap in the centre of the back. 2nd to the centre of the back. 3rd from the centre of the back right to the centre of the back at the socket bone. 4th from the joint

From the shoulder to the socket bone, 5" from same to centre of the back on the top, 6" from same under the arm to the socket bone 7" from same to any point between Centre of the back and waist to be determined by the shoulder blades. 8" From same to the centre of the waist. For the purpose of drafting the garment we use a square of the following construction. it is an oblong twenty four inches by four inches (as represented in Fig 4) the inches being marked on the inner edge, and the flat side (between the edge when the inches are marked and the ruler edge) containing a groove in which the scales are inserted which are used in drafting garments - having four sides it will hold a sufficient number of scales for drafting any garment and by the figures on the different sides we are enabled to take any angle that would facilitate the cutter in his operation. By placing the square on any line with the corner at any given point and taking any number on the other side or end, any angle may be obtained which the draft may require. By this it will be seen that it possesses the advantages of the square protractor and measure case.

The curve of the waist represented by the line B. C. D in Fig 4, and the spring of the skirt are taken as follows - Take the size of the waist and hips, then by the difference between the two, a scale is selected with which we measure up the side from the whole difference, then this difference is to be added to the front line of the skirt at the top. The angle formed by the uniting of the back and top lines of the skirt should be a right angle, and before the addition of the difference between the hips and waist is made, about one inch should be added to the top line in front to give the natural spring. We claim to be the inventors of the scale on the groove of the standard by which the angles of the body and a certain garment, point for the waist are ascertained, and of the straps by which the various curves and inequalities on the surface of the body are measured. We also claim to have invented the square described, and the manner of ascertaining the curve of the waist and spring of the skirt.
